SAFETY STIRRUP

Carl M. Jahn, 2640 St. Paul St., Denver, Colo.
Filed Sept. 28, 1964, Ser. No. 399,483
10 Claims. (Cl. 54—49)

The present invention relates to equestrian apparatus and more particularly to a new and improved stirrup for use on a riding saddle.

The principal object of the present invention is to promote the safety of a horseback rider by preventing the rider's foot from becoming accidentally caught or entangled in a stirrup while the rider is mounting or dismounting, or in the event the rider falls, slips, or is thrown from the horse.

It is an object of this invention to construct a stirrup in a manner such that a rider's foot can be readily released or removed therefrom, and in such a manner that a foot cannot become entangled therein. More specifically, it is an object of this invention to provide a stirrup which will swing or pivot with respect to the stirrup strap in order that the rider's foot will be quickly and easily released therefrom, and constructed so that a rider's foot and angle cannot pass completely through it.

Another object of the present invention is to provide a stirrup which will adjust to a position which facilitates the insertion or withdrawal of the rider's foot when mounting or dismounting.

Other objects and advantages of the present invention will become apparent as the following description proceeds taken in connection with the accompanying drawings wherein:

FIGURE 1 is a front view of a stirrup strap and stirrup embodying the present invention.

FIG. 2 is an elevation view of the stirrup mechanism shown in FIG. 1.

FIG. 3 is an enlarged fragmentary view of the stirrup shown in FIG. 1, with portions cut away, illustrating a pivot and roller mechanism forming a part of the present invention.

FIG. 4 is a front view of a stirrup embodying a modified form of the present invention.

FIG. 5 is an elevation view of the stirrup mechanism shown in FIG. 4.

FIG. 6 is a section view taken substantially in the plane of line 6—6 on FIG. 4.

FIG. 7 is a plan view of still another form of stirrup embodying certain features of the present invention.

While certain illustrative forms of the invention are shown in the drawings and will be described below in considerable detail, it should be understood that there is no intention to limit the invention to the specific forms and modifications disclosed. On the contrary, the intention is to cover all modifications, alternative constructions, equivalents and uses of the present invention falling within the spirit and scope of the invention as expressed in the appended claims.

Those skilled in the equestrian arts will appreciate that a conventional form of stirrup (not shown in the drawings) is attached to a riding saddle by means of a stirrup strap which is looped at each end, with one loop engaging the stirrup and the other loop engaging the saddle. These straps are adjustable so that the saddle and stirrup may be adjusted according to the characteristics of an individual rider. When in use, the stirrup strap is twisted through a quarter revolution so that the rider's feet can readily engage in the depending stirrups. Such a conventional stirrup may take a number of forms, a common form of which is a generally U-shaped member, the free legs of which are pivotally mounted on a pin or the like passing through the loop in the stirrup

2

strap. Because the stirrup strap must be twisted so that the stirrup faces outwardly of the horse when the rider is mounting or dismounting, the rider occasionally encounters some difficulty in conveniently placing his foot in the stirrup or in removing it from the stirrup. Also, the rider is subjected to some risk of having his foot pass completely through the stirrup, thereby causing it to become entangled, and this mishap is particularly serious if the rider falls or is thrown from the horse.

The present invention, meeting the objects set forth above and as shown in the drawings, has been found to substantially overcome these foregoing difficulties. To this end, the present invention is embodied in a safety stirrup, indicated generally as 20 in FIG. 1, which stirrup depends from a conventional adjustable stirrup strap 21. Essentially, the safety stirrup 20 comprises a lower, generally U-shaped stirrup 22 swingably connected by means of an intervening yoke assembly 24 to the adjustable stirrup strap 21. In this manner, a compound swinging movement is afforded so that the stirrup member 22 can swing relative to the yoke assembly 24, as shown in FIG. 2, and at the same time the yoke assembly itself can swing with respect to the stirrup strap.

The yoke assembly 24 is, in the illustrative form shown in FIG. 1, constructed of a pair of arcuate yoke members 25, each being channel shaped in cross section so as to provide a pair of opposed ribs 26, 27 joined by a web 28. For swingably securing said yoke members 25 to the stirrup strap 21, the members are formed at their upper free ends with an aperture extending through which is a bolt or pin 31, having a head 32 on each end thereof. This pin 31 in turn passes through a sleeve 34 positioned inside the loop in the stirrup strap 21 so that each yoke member 25 is pivotally or swingably suspended from the strap 21. It should be appreciated that any appropriate pin construction can be provided, and the pin may be either permanent or replaceable.

For purposes of swingably suspending the stirrup 22, the arcuate yoke members 25 are each provided at their lower ends with an aperture 35 defined by an outwardly struck boss 36 on which is swingably mounted the upper end of the corresponding leg of the stirrup 22. To this end, each leg of the U-shaped stirrup is provided with an aperture 38 of a size sufficient to fit over the boss 36, and the stirrup leg is held on the boss 36 by means of an appropriate rivet 39 or other fastener having opposed heads 40, 41, one of which engages the stirrup leg, as shown in FIG. 3. The illustrative form of a stirrup member 22 shown in FIGS. 1-3, comprises a generally U-shaped channel member defining a foot-supporting base 42 having upwardly extending legs 44, 45 on each end thereof extending upwardly into swingable engagement with the arcuate yoke members 25. The stirrup is formed of channel shaped material which define strengthening ribs 46, 47 extending downwardly and outwardly along the edges of the base 42 and legs 44, 45.

When a rider inserts his foot through a stirrup, his toe passes through the stirrup from one side, herein referred to as the heel side of the stirrup or the side toward the rear of the saddle to the other side which will be referred to as the toe side of the stirrup or the side toward the front of the saddle. Referring to FIG. 2, the rib 46 defines the heel side, and the rib 47 defines the toe side of the stirrup 22. To insure that the rider's foot will not be caught in the stirrup, it is desirable that the stirrup swing forwardly or in the direction of the toe side. Accordingly, the arcuate yoke members 25 are positioned in such a manner that the yoke members 25 are convex in the direction of the toe side of the stirrup shown in FIG. 2, and stop means are provided to pre-

vent a similar swinging movement toward the heel side of the stirrup.

One illustrative stop means on the stirrup shown in the drawings is formed by the rib 46 on the heel side of the stirrup which engages the rib 27 on the heel or concave side of the arcuate yoke member 25. In this manner, the abutting ends or edges of the ribs 46 and 27 form stops which prevent a regressive or heel-direction swinging of the stirrup 22. To insure that the stirrup may swing forwardly, the corresponding rib 47 on the toe side of the stirrup and the rib 26 on the convex side of the arcuate yoke members, are each cut so as to terminate short of the pivot or hinge joint and are thus spaced apart as shown in FIG. 2.

In order to prevent the rider's foot from slipping through the stirrup 22, means are provided to engage the instep of the rider's foot before the heel has passed completely through the stirrup. To this end, there is provided a roller 50 or other instep engaging means mounted between the yoke members 25 in a position parallel to and overlying the base 42 of the stirrup 22. It has been discovered that the use of a roller is particularly desirable in that it affords an easy withdrawal of the rider's foot from the stirrup and prevents the foot or the rider's shoe from catching or becoming entangled in the yoke assembly.

For mounting the roller 50 in the yoke assembly 24 between the arcuate yoke members 25, each such yoke member 25 is provided with one or more mounting holes 51 through which screws 52 or other fasteners extend into engagement with a roller pinion or spindle 54 on which the roller 50 is pivotally supported. The roller spindle 54, being fixed between the yoke members 25, further serves to add support to the yoke and thereby increases the strength of the yoke assembly 24.

It should be observed that the combination of the roller with the swinging mounting of the stirrup adds a further safety feature in that as the stirrup 22 swings forward with respect to the yoke assembly 24 the vertical distance between the base 42 of the stirrup and the roller 50 decreases as is clearly shown in FIG. 2. This movement results in a decrease of the vertical space available for the rider's foot, which slides off the base 42 of the stirrup, is forced outwardly from the stirrup, and is thereby prevented from becoming entangled or hooked in the stirrup.

Turning now to certain modified forms of the present invention, there is shown in FIGS. 4, 5 and 6 a stirrup construction similar to that described above, but with means providing for a vertical pivoting movement of the yoke and stirrup with respect to the stirrup strap. It will be appreciated that when a rider is mounting or dismounting it is necessary to turn the stirrup so that it is facing outwardly from the horse, so that the rider can insert or withdraw his foot from the stirrup. To facilitate this pivoting movement, there is provided a yoke similar to that described above, but constructed in two parts which are pivotally joined together as shown in FIGS. 4 and 5. To this end, there is provided a U-shaped lower yoke member 60 the horizontal portion or top 61 of which is pivotally connected to the horizontal portion or base 62 of a similar U-shaped upper yoke member 64. The upper U-shaped member 64 is swingably mounted on the lower end of a stirrup strap in the same manner as described above and shown in FIG. 1, while the lower U-shaped member 60 supports a stirrup, again in a manner like that shown in FIG. 1. It is not believed necessary at this point to describe in detail the connection between the upper yoke member 64 and the strap 21a except to note that it includes a sleeve 34a received within the lower loop of a stirrup strap 21a and swingably supporting a stirrup bolt or pin 31a extending between legs 65 of the upper yoke member 64. Similarly, as described above, the lower yoke member 60 comprises generally arcuate yoke members 25a between which is mounted a roller 50a and swingably depending from which is a stirrup 22a.

While any appropriate pivot connection may suffice, it has been discovered that by providing a pivot connection which affords a releasable friction engagement between the upper and lower yoke members is preferable.

5 To this end, the horizontal portion or top 61 of lower yoke member 60 and the horizontal portion or base 62 of the upper yoke member 64 are each constructed so as to be generally channel shaped as shown in FIG. 6, with the webs of the opposing channels abutting each other and held together by means of a rivet or other fastener 66 and an interposed leaf spring 68. If desired, an additional leaf spring may be employed at the opposite end of the rivet 66 to give added flexibility.

15 In order to prevent the stirrup strap and upper yoke member portion 64 from interfering with the rider's foot or leg, the pivot is desirably placed off-center as shown in FIG. 4. More particularly, this off-center pivot should be located toward the outside of the stirrup and yoke, that is toward the side away from the horse when 20 the rider is mounted. As viewed in FIG. 4, the right side of the stirrup would be the side closest to the horse, and it will be noted that the pivot is nearer the left side, or the side away from the horse. In this manner, as 25 the stirrup pivots it will be positioned outwardly and away from the horse, giving additional clearance for the rider's foot. The position of the stirrup when the yokes 60, 64 are pivoted with respect to one another is shown in FIG. 5. The pivoting movement is accomplished by the rider placing some weight or a downward force on 30 the stirrup as he pivots it with respect to the stirrup strap. This force, acting against the spring 68, separates the yoke members so that they may be turned with respect to one another. When the force is released, the yoke members are once again urged tightly together and 35 remain in the position in which they were left.

To further the ease of withdrawal or insertion of the rider's foot into a stirrup, there is provided still another modified form of stirrup as shown in FIG. 7. In this form, a conventional U-shaped stirrup 70 is provided with a base roller 71 and one or more side rollers 72, 73. These rollers may be mounted in the stirrup in any conventional manner such as by the pins 74 as shown in FIG. 7. With this construction, together with the swinging or pivotal mounting of the stirrup on a yoke 75, a rider's foot is easily inserted or withdrawn from the stirrup. The rollers reduce the friction between the foot and the stirrup and thereby enhance the safety characteristics of the stirrup.

It should be appreciated that various combinations of the features shown may be used. For example, the stirrup shown in FIG. 7 may be employed, in lieu of the U-shaped stirrup 22, with the yoke mechanism shown in FIGS. 1 and 2, or with the yoke mechanism shown in FIGS. 4 and 5. Alternatively, one or both of the side rollers 72, 73 may be omitted, or the base roller 71 may be omitted and the side rollers 72, 73 only employed. It should also be appreciated that by providing a plurality of holes 51 as shown in FIG. 2, the instep engaging roller 50 may be adjusted to accommodate different riders.

I claim as my invention:

60 1. A safety stirrup for use on a saddle having a stirrup strap depending therefrom, said safety stirrup comprising, in combination, a U-shaped stirrup, a pair of spaced arcuate yoke members, means extending between corresponding ends of said yoke members and swingably supporting the same on the stirrup strap with said arcuate yoke members positioned so as to be convex toward the front of the saddle, means swingably mounting the opposite ends of said yoke members to corresponding legs of said U-shaped stirrup, stop means on said U-shaped 65 stirrup engageable with corresponding stop means on said yoke members for limiting swinging movement of said U-shaped stirrup in the direction toward the rear of the saddle, and means rotatably mounted between said yoke members and overlying said stirrup for engaging a rider's foot and preventing the same from slipping through the 70 75

stirrup, said rotatable means acting against a rider's foot to force the same out of the stirrup when said stirrup swings in the direction toward the front of the saddle.

2. A safety stirrup for use on a saddle having a stirrup strap depending therefrom, said safety stirrup comprising, in combination, a stirrup, means comprising a pair of spaced arcuate yoke members joined at their upper ends to a pin engaged with said stirrup strap and pivotally connected at their lower ends to respective ends of said stirrup, said arcuate yoke members being convex toward the front of said saddle, stop means on said arcuate yoke members engageable with corresponding stop means on said stirrup for limiting swinging movement of said stirrup in the direction of the rear of the saddle, and a foot-engaging roller mounted axially between said arcuate yoke members for engaging a rider's foot when said stirrup swings in the direction of the front of the saddle, whereby a rider's foot is precluded from becoming entangled in said stirrup.

3. A safety stirrup as defined in claim 1 wherein said U-shaped stirrup has a roller mounted in the base thereof.

4. A safety stirrup as defined in claim 1 wherein said U-shaped stirrup has a pair of opposed rollers mounted in the legs thereof for engaging the sides of a rider's foot.

5. A safety stirrup as defined in claim 1 wherein said rotatable means is mounted between said arcuate members so that said rotatable means is away from a rider's foot when said foot is in normal riding position in said stirrup.

6. A safety stirrup as defined in claim 1, wherein said means extending between corresponding ends of said yoke members and swingably supporting the same on the stirrup strap includes a pivot means whereby said stirrup can pivot about a vertical axis relative to said stirrup strap.

7. A safety stirrup as defined in claim 1, wherein said means extending between corresponding ends of said arcuate yoke members and swingably supporting the same on the stirrup strap includes a first yoke means, means

swingably mounting said first yoke means on the stirrup strap, second yoke means incorporating said arcuate yoke members, and means pivotally connecting said first yoke means to said second yoke means, said pivotally connecting means being off-center in a direction away from the saddle and releasably holding said first and second yoke means together in frictional engagement, whereby said stirrup can be pivoted about a vertical axis relative to said stirrup strap.

10. 8. A safety stirrup as defined in claim 7, wherein said rotatable means is mounted between the arcuate members of said second yoke means so that said rotatable means is away from a rider's foot when said foot is in normal riding position in said stirrup.

15. 9. A safety stirrup as defined in claim 7, wherein said U-shaped stirrup has a roller mounted in the base thereof.

10. A safety stirrup as defined in claim 7, wherein said U-shaped stirrup has a pair of opposed rollers mounted in the leg thereof for engaging the sides of a rider's foot.
